UNITED STATES PATENT OFFICE

JAMES A. PALMER, OF TAUNTON, MASSACHUSETTS, ASSIGNOR TO TAUNTON PEARL WORKS, INC., A CORPORATION OF MASSACHUSETTS

NECKTIE HOLDER

Application filed August 7, 1931. Serial No. 555,677.

This invention relates to a necktie clasp for holding a four-in-hand necktie in position on the shirt of the wearer, and has for its object to provide a necktie holder which 5 will remain in the desired position relative to the tie and be prevented from rocking or pivoting about a point of engagement.

Another object of this invention is the provision of a necktie holder or clasp which 10 may easily slide along the parts to be gripped to maintain the tie in fixed position on the shirt and yet one which will be securely held on the parts to be gripped when moved to desired position.

15 A further object of this invention is to provide a necktie holder which will be of simple construction and formed of two parts, one part being from bent-up wire, and the other formed from sheet stock suitably pierced 20 and bent.

A still further object of this invention is the provision of a tie holder which will grip the tie and shirt at spaced points by means of a separate member which may rock or tilt 25 with reference to the jaw upon which it is pivoted, whereby a leverage is obtained for easily opening the jaws of the clasp when the same is mounted on the material it is to grip.

30 With these and other objects in view, the invention consists of certain novel features of construction, as will be more fully described, and particularly pointed out in the appended claim.

35 In the accompanying drawing:

Fig. 1 is a top plan view of the tie holder.

Fig. 2 is a bottom view thereof.

Fig. 3 is a side elevation.

40 Fig. 4 is a view similar to Fig. 3, with the gripper member removed.

Fig. 5 is a plan view of the structure shown in Fig. 4.

Fig. 6 is a plan view of the gripper member alone.

45 Fig. 7 is the central sectional view through the gripper.

Fig. 8 is a section on line 8-8 of Fig. 7.

Fig. 9 is a section on line 9-9 of Fig. 2.

50 In the construction of tie holders, an ornament or the like is frequently mounted on

the holder, in which case it is desirable that the tie holder remain in a given set position when in engagement with the tie and shirt. Tie holders frequently have but a single point of engagement between the jaws thereof, in 55 which case the holder will rock about this point of engagement to allow one end of the holder to drop out of desired position, thus providing an untidy appearance, especially 60 is this the case where an ornament such as a picture or the like is mounted upon the holder; and in order to avoid this undesirable result, I have provided a holder which 65 will grip the material at two widely spaced points and thus prevent a rocking or tilting 70 action, and in the construction of such a clasp I have pivotally mounted the gripping member so that the same may be easily moved into gripping position on the tie and fabric 75 of the shirt, and the following is a detailed 80 description of the present embodiment of this invention, illustrating the preferred means by which these advantageous results may be accomplished.

With reference to the drawing, the body 75 member of the holder is shown in Figs. 4 and 5, and consists of a length of wire here shown as round in cross section, folded upon itself as at 10 to provide a loop 13 with parallel 80 portions 11 and 12 in contact or close adjacency, extending therefrom. The loop 13 is of any desired shape or configuration that illustrated being an open square 14, although any suitable shape or enlargement may be 85 provided as desired. The opposite ends of the wire thus folded are spaced to provide parallel portions 15 and 16, with the ends thereof 17 and 18 turned inwardly to provide pivoting trunnions for the gripper; and the wire thus shaped is again folded as 90 at 19, to provide spaced jaw portions 20 and 21 as illustrated in Fig. 4, with the jaw portion 21 extending but a portion of the length of the jaw portion 20 comprising the more 95 closely spaced portions of the jaws 11 and 12.

The gripper member is formed from a flat strip of sheet metal, designated generally 22, which is pierced as at 23, leaving a central strip 33, and is bent to provide longitudinal 100 convex portions 24, adjacent either end.

These portions, however, are concave laterally as at 34 (see Fig. 9) to receive the opposite jaw of the clasp. Ears 25 are formed at either side of the gripper and are folded at 5 right angles to the general plane of the stock, while portions of the stock of the gripper are cut out as at 26 on either side of the center and are folded to provide a tubular bearing 27, meeting in a seam 28 into which ears and 10 bearing the trunnions 17 and 18 may be positioned, such as by springing the parallel wires 15 and 16 apart and then inserting them from opposite directions into the bearing thus formed between the ears and tube, thus 15 providing a rockable, hinged or pivoted support for the gripper member.

In order that the trunnions 17 and 18 may not be accidentally detached, I bind the body wires together with a band 29 located adjacent 20 the opening or space between them. The holder thus assembled has the concavo convex portions 24, contacting with the closely spaced wires 11 and 12 of the jaw 20 at points 30 and 31, the convex portion at the outer 25 end providing a mouth 32 for the insertion of the fabric therein.

In use, as the fabric is inserted into the mouth 32, the outer end portion of the gripper will move outwardly, acting as a lever 30 fulcruming about the point 31 to move the jaw 21 as shown in Fig. 4 against the spring of the stock away from the jaw 20. After the fabric has reached the second contact 35 point 31, further movement thereof into the clasp will cause the gripper to pivot about the point 30, which slides along the fabric as inserted, thus further raising or spreading apart the jaws 20 and 21. The action of springing apart of the wire jaws for insertion 40 is made easy by the long leverage of the gripper.

When the clasp is in working position with the tie and shirt positioned between the jaws thereof, the pressure of the jaws toward each 45 other causes the material therebetween to be gripped at the contact points 30 and 31 with the desired pressure, and prevents rocking or slipping of the clip with reference to the material it engages. The gripper is pivoted 50 midway between its ends to one of the jaws, thus causing an equalizing of pressure and preventing the article from tipping. Further, this construction permits of a larger or 55 thicker fabric being gripped without distortion or setting of the spring action of the jaws.

In order to more securely hold the parts in position, I concave the central portion 33 of the gripper as at 34, (see Fig. 9) to present a 60 larger gripping surface to the fabric.

The foregoing description is directed solely towards the construction illustrated, but I desire it to be understood that I reserve the privilege of resorting to all the mechanical 65 changes to which the device is susceptible,

the invention being defined and limited only by the terms of the appended claim.

I claim:

A necktie holder comprising a length of wire doubled upon itself and then again folded upon itself providing opposed portions, one portion having the wires running parallel and in close adjacency, and the other portion being shorter and having the wires extending parallel and spaced a substantial distance apart with their extremities bent to extend toward each other; a sheet metal member provided at its middle with a bearing pivotally mounted on said inwardly extending portions and the portions of said member between the pivot and ends bent toward and in contact with the closely lying wires with the end turned away from said wires and presenting a longitudinally convex surface at the points of contact and providing a mouth for the insertion of material to be gripped therebetween, said convex surface being transversely concave at the point of contact.

In testimony whereof, I affix my signature.

JAMES A. PALMER.
